UNITED STATES PATENT OFFICE.

WILLIAM HUPPERT, OF NEW YORK, N. Y.

DESIGN FOR AN ELECTRICAL SOCKET.

Application filed April 28, 1927. Serial No. 21,781. Term of patent 7 years.

To all whom it may concern:

Be it known that I, WILLIAM HUPPERT, a citizen of Czechoslovakia, residing at 1184 Lexington Avenue, in the borough of Manhattan, city, county, and State of New York, have invented a new, original, and ornamental Design for Electrical Sockets, of which the following is a specification, reference being had to the accompanying drawings, forming part thereof.

Fig. 1 is a side elevation of an electrical socket embodying my new design; and Fig. 2 is a plan view of the same.

I claim:

The ornamental design for an electrical socket, as shown.

WILLIAM HUPPERT.
